I claim the ornamental design for a frame for outdoor power equipment, as shown and described.

DESCRIPTION

FIG. 1 is a front perspective view of a frame for outdoor power equipment showing my new design;

FIG. 2 is a left side view thereof;

FIG. 3 is a front view thereof;

FIG. 4 is a right side view thereof;

FIG. 5 is a rear view thereof;

FIG. 6 is a top plan view thereof;

FIG. 7 is a bottom plan view thereof; and,

FIG. 8 is a perspective view thereof, shown in an alternate configuration.

The broken lines shown represent unclaimed subject matter and form no part of the claim. Where broken lines abut a claimed surface it is understood that those broken lines represent an unclaimed boundary between claimed and unclaimed surfaces. None of the broken lines form any part of the claimed design.
